COMBINED LIGHTER AND TIE CLIP

Gerda Blau, New York, N. Y.

Application July 12, 1950, Serial No. 11,094

Term of patent 3½ years

(Cl. D48—27)

To all whom it may concern:

Be it known that I, Gerda Blau, a citizen of the United States of America, residing in New York city, county of Bronx, and State of New York, have invented a new, original, and ornamental Design for a Combined Lighter and Tie Clip, of which the following is a specification, reference being had to the accompanying drawing, forming part thereof, wherein,

I claim:

The ornamental design for a combined lighter and tie clip, substantially as shown and described.

GERDA BLAU.
